UNITED STATES PATENT OFFICE

2,255,147

COMBINED CALCULATING, REGISTERING,
AND TICKET PRINTING MACHINE

Daniel Broido, Belsize Park, London, England

Application May 21, 1937, Serial No. 144,022
In Great Britain May 28, 1936

4 Claims. (Cl. 235—61)

This invention relates to combined calculating, registering and ticket printing machines, and in particular to apparatus for registering information represented by similarly shaped, but differently positioned marks distinguishable solely by their respective positions on a carrier, the transparency of said marks being different to that of the carrier.

The object of the invention is to provide a simplified transmission and registering mechanism accurately controllable by a scanning mechanism provided for analysing or reading said marks.

A further object of the invention is to provide light-controlled scanning and transmission mechanisms operating more rapidly than such mechanisms hitherto proposed.

The invention will now be described with reference to a multiplying cash register having a predetermined range of prices and a predetermined range of weights.

In the accompanying drawings which illustrate an embodiment of this invention:

Figures 1A and 1B illustrate partly in plan view and partly in section approximately on line I—I of Figure 7 the general arrangement of a machine;

Figures 2A and 2B are a side elevation of a complete arrangement;

Figures 3A and 3B are a side elevation of a screen for setting different weights and prices per unit;

Figure 4 illustrates in side elevation (section taken on line IV—IV of Figure 1) the key-board for setting the prices per unit;

Figure 5 illustrates a portion of a slotted screen drawn to an enlarged scale;

Figure 6 illustrates in plan details of the device for locking the keys for setting the prices per unit;

Figure 7 is a section on line VII—VII of Figure 2 through the result mechanism;

Figure 8 illustrates in plan the position of the relay armature as shown in Figure 7;

Figures 9 and 10 illustrate in end elevation different positions of the cam and relay armature;

Figures 11 and 12 illustrate the position of said parts in plan;

Figure 13 is a vertical section (developed) on line XIII—XIII (drawn to an enlarged scale) of Figure 7;

Figure 14 is a section on line XIV—XIV of Figure 13;

Figure 15 is a sectional plan on line XV—XV of Figure 7 of part of the printing device;

Figure 16 is an end view thereof;

Figure 17 is a sectional plan on line XVII—XVII of Figure 7 of the ticket delivery roller and the ink roller;

Figure 18 is a sectional plan partly on line XV and partly on line XVII of Figure 7 of the drive of the ticket-delivery roller;

Figure 19 is an end view thereof;

Figure 20 is a vertical section on line XX—XX of Figure 1 illustrating the main driving device;

Figure 21 is a vertical section on line XXI—XXI of Figure 20;

Figure 22 is a plan of a detail part shown in Figure 20;

Figure 23 is a similar view showing the parts in a different position;

Figure 24 illustrates diagrammatically an arrangement embodying the use of a flat scanning disc;

Figures 25A and 25B are views similar to Figures 3A, 3B, illustrating a modified form of screen mechanism;

As shown in Figures 1A, 1B the machine is furnished with two independent key-boards, one for setting the prices per unit having a plurality of keys 1 and the other for setting the weights having a plurality of keys 2. Each of the keys 1

is mounted on a bar 3 in frames 4, 5, and is pivotally connected at its lower end by means of a stud 6 to a bell-crank-lever 7 (Figure 4) mounted on a bar 8, which lever 7 is connected to a wire 9 actuating a stop lever 10. On depressing

35 a key 1, the wire 9 is pulled around bar 11 angularly mounted in bracket 12 and causes a stop lever 10 to be brought against a stop bar 13 against the tension of a spring 14 fixed to bar 15. In this position, lever 10 prevents all screens

40 16 actuated by the keys 2 slidably mounted on bars 17 from moving higher up when being operated, as on depressing a key 2 it stretches a tension spring 18 which causes the screen 16 connected to it to swing around bar 19 until its lower end 20 comes to rest against one of the stop levers 10 being now in the working position (Figures 2A, 2B). Stop levers 10 are rockably

45 mounted on bar 21 and held in position by means of spacers 22. The stop levers 10 and keys 1 are maintained in position as shown in Figures 4 and 6 by a locking frame 23 arranged to slide in oblong holes 24 under influence of springs 25 fixed to studs 26 in frame 23 and to studs 27 in the machine frames 4, 5. On depressing a key 1, the frame 23 is pulled in the space between projec-

tions 28 and 29 on this key 1 and locks it in this position. When a second key 1 is depressed, the projection 28 thereon pushes the locking frame 23 to the left so that the first key 1 is released and returned into initial position by means of spring 14.

A similar locking frame 30 is provided for keyboard 2 (Figures 3A, 3B) which frame coacts with faces 31 on keys 2.

The arcuate portion of the result screens 16 (Figure 3) is provided with slots 32 representing the different items in a manner fully described in the specification to my British Patent No. 446,338. For instance, each screen may be divided into three longitudinal areas I (containing slots representing the weight), II (containing slots for different prices per unit) and III (for slots representing the results of multiplication). Area I is sub-divided into two smaller areas a, b, containing slots for pounds and parts of a pound respectively; area II is sub-divided into three areas c, d, e, for dollars, tens of cents and cents respectively, and area III is subdivided into areas f, g, h, in a similar manner. Furthermore, the small areas a to h are again sub-divided into even narrower areas, as shown in Figure 5, according to the number of numerals in each digit. In the example shown in Figure 5 the slots represent:

$$2\frac{3}{4} \text{ lbs.} \times \$1.55 = \$4.26.$$

It is understood that actual slots 32 can be replaced by any mark or prints on screens 16 provided that their transparency differs from that of the screens themselves. For instance, the result screens 16 may consist of a non-transparent or opaque material, the different items being represented by transparent spots, or vice-versa.

The result screens 16 (Figures 1A, 1B and 3A, 3B) are arranged to be brought in front of a transmission mechanism comprising, on one side of the screens 16, a source of light energy such as an electric lamp 33 mounted within a suitable housing denoted generally by 34 and on the other side of said screens 16, a light sensitive cell 35 rigidly supported by bracket 36 within the interior of a rotary cylinder 37 or behind a rotary disc (hereinafter referred to as the scanning screen) and a magnetic relay 38 (Figure 7) controlled by the light sensitive cell 35. The electric lamp 33 is adapted to produce a suitable beam of light, and its housing 34 may comprise reflectors or lenses adapted to make the beam substantially parallel. The housing 34 is provided on the side adjacent the screens 16 with an opening, the size of which is substantially equal to the area occupied by a radial line of slots 32 on any screen 16. In this manner, a narrow beam of substantially parallel light is projected on to the light sensitive cell 35 just over the tops of the screens 16 when in the lowermost or normal position. When a key 1 is depressed, it operates its associated stop 10 as already described, which determines the amount of lift of any of the screens 16, one of which may now be raised by depressing one of the keys 2. Thus, the selected screen 16 is interposed in the path of light, so that only the selected row of slots 32 is exposed to the narrow beam of light. As the beam is substantially parallel and level, the same line of slots 32 (determined by the depressed key 1) is illuminated, whether a screen $\frac{1}{4}$ " close to the lamp 33 (Figure 1) or a screen

"5" further away from the lamp is brought into the working position.

The scanning screen 37 may consist of a non-transparent cylinder, disc or the like furnished with a plurality of slots or transparent spots 39 (Figures 2A, 2B) arranged along a helical line. The number of the slots 39 or the like in the scanning screen 37 is equal to the total number of numeral areas in a row of slots 32 on the result screens 16 and the pitch of the helix equals the horizontal length of a row of slots 32 on said result screens 16. Thus at a given instant only one scanning slot 39 is in front of the set row of result slots 32, and in one complete revolution of the scanning screen 37 the beam of light passing from the source 33 to the light sensitive cell 35 moves from one end of the set row of result slots 32 to the other.

The scanning screen 37 is rigidly mounted by means of pin 40 on to the end of a driven spindle 41 suitably supported in bearings 42, 43 in the main frame members 44, 45 of the machine. The spindle 41 on which the scanning screen 37 is mounted is provided with a pinion 46 arranged to mesh with a driving pinion 47 loosely mounted on the main actuating shaft 48 rotatably mounted in bearings 49, 50 in the main frame members 44, 51 of the machine (Figures 1A, 1B and 20) and driven by a hand actuated gear segment 52 meshing with a pinion 53 keyed on the main actuating shaft 48. The gear segment 52 is actuated by a handle 55 secured thereto by a nut 56; said gear segment 52 is pivoted on stud 57 fixed to the frame member 44 by nut 58. The pinion 53 is prevented from sliding axially on shaft 48 by a set screw 59. The driving pinion 47 is furnished on its back face with a clutch member provided with a projection 60 with which a clutch member 61 actuated by a spring 62 coacts, said clutch member being so mounted on the main actuating shaft 48 that it is free to slide axially thereon along key 63 under influence of the spring 62 but rotates with said shaft. The driving pinion 47 is further provided on its front face with a stop stud 64 arranged to coact with a trigger member 65 pivotally mounted on a pin 66 in a bracket 67 secured to the frame of the machine by screw 68, said trigger member 65 being controlled by a flat spring 69, the arrangement being such that on one complete revolution of the driving pinion 47 further rotation is stopped and the clutch member 61 is forced rearwardly by reason of the cam-shaped projection 60 on pinion 47, thereby causing a pin 70 secured therein to pass into a hole 71 provided in an intermediate gear wheel 72 meshing with a gear wheel 73 mounted on a spindle 74 on which the numeral wheels 75 are mounted. The position of the trigger 65 at the beginning of the forward stroke of handle 55 is shown in Figure 22, whereas its position at the beginning of return stroke is illustrated in Figure 23. As shown in Figure 21 the handle 55 slides in an arcuate slot 76 in the frame member 44 and is returned into initial position by means of a spring 77 fixed to stud 78. A washer 79 is preferably placed between the inner end of the bearing 50 and the boss on the gear wheel 72.

The driven spindle 41 (Figures 1A, 1B) on which the scanning screen 37 is mounted is further provided with a plurality of gear segments 80 secured by pins 81 and arranged to actuate a corresponding number of toothed sleeves 82 mounted on a spindle 83 arranged in bearing 84, 85 parallel with the scanning spindle 41 (see also

Figure 7). 86 and 87 are spacers. Rigidly mounted on each toothed sleeve 82 is a stop wheel 89 (Figure 13) with which a spring actuated pawl 90 mounted on spindle 91 is adapted to engage when the gear segment 80 is out of engagement with the wheel bush 82. Each of said sleeves 82 is furnished with a key 92 engaging a slot 93 provided in a clutch member 94 so that the latter is free to slide axially on said bush but is compelled to rotate therewith.

The clutch members 94 are moved axially on the sleeves 82 by means of spring controlled clutch forks 95, the opposite ends of which are caused to bear against levers 96 (hereafter referred to as relay armatures) rockably mounted on a shaft 97 slightly above their centre, the lower ends of said relay armatures 96 being drawn against a plurality of rotary cam wheels 98 by springs 99 (Figure 7). The clutch forks 95 are rockably mounted on pins 100 in a square bar 101, to which the flat springs 102 are fixed by means of screws 103 (Figure 13). The cams 98 are secured by pins 104 to a shaft 105 furnished adjacent the front of the machine with a toothed wheel 106 (Figures 2A, 2B and 20) arranged to mesh with the driving pinion 47, said cams 98 being arranged to move the relay armatures 96 from the initial position shown in Figures 9 and 11, into the working position shown in Figures 10 and 12 within magnetic reach of the relay 38 adapted to be actuated by current controlled by the light sensitive cell 35. The said relay armatures 96 are moved into the aforesaid working position (as shown in Figures 7 and 8) at the same moment as the corresponding gear segment 80 commences to turn the sleeve 82 belonging to the same unit and the corresponding slots 39 in the scanning screen 37 move in front of the set row of slots 32 in the result screen 16 then in set position.

Each of the aforesaid clutch members 94 is provided with a pin 107 adapted to engage a recess in a further stop wheel 108 controlled by a pawl 109 and spring 110 and rigidly connected to a pinion 111 which is loosely mounted on the shaft 83 and is arranged to mesh with a pinion 112 rigidly connected to a numeral wheel 75 rotatably mounted on a shaft 74.

The shaft 74 of the numeral wheels 75 is furnished at each end with an eccentric sheave 113 (Figures 15 and 16) on key 114, each of which sheaves 113 supports an arm 115 between and to which is secured by screws 116, 117 a bracket 118 slidably mounted in the main frame plates 45, 51 in a slot 119 and supporting an india-rubber pad 120, the arrangement being such that as the shaft 74 rotates the pad 120 is reciprocated towards and away from the numeral wheels 75, the numbers that have been transferred thereto being printed on a sheet of paper 121 from a reel 122 disposed on shaft 123 adjacent the reciprocating arm, ink being supplied to said numeral wheels 75 by a suitably disposed inking roller 124 on shaft 125 (Figures 7, 17), which is also provided with rubber rollers 126 for feeding the paper. With feed rollers 126 coat rollers 127 fixed on shaft 128 by pins 129, said shaft 128 being driven by ratchet wheel 130 fixed to it by pin 131 and by a pawl 132 mounted on stud 133 in pinion 134, to which is also fixed a flat spring 135 on stud 136 (Figures 18 and 19). Pinion 134 is loosely mounted on the hub of the ratchet wheel 130 and is driven by gear 137 fixed to shaft 74 of the numeral wheels 75 by pin 138.

Broadly stated, the arrangement of the trans-

mission mechanism is such that one transmission unit (comprising a group of nine slots 39 on the scanning screen 37, a toothed sleeve 82 driven by a gear segment 80, a numeral wheel 75 driven by a clutch member 94 which is turned by the said toothed sleeve 82, a clutch fork 95 operated by a relay armature 96 and a cam 98 controlling the said relay armature 96) is provided for each denomination to be transferred from the result screens 16 on to the numeral wheels 75. The said denominational transmission units work consecutively. The numeral wheel 75 on a working transmission unit is stopped as soon as a slot 39 on the scanning screen 37 is in front of a slot 32 on the result screen 16, whereby the position of the numeral wheel 75 (e. g. the numeral which it turns towards the printing device 120) corresponds to the position of the said scanning slot 39. The complete transmission of all digits is effected during one single revolution of the scanning screen. The electric lamp 33, the light sensitive cell 35, and the magnetic relay 38 are common for all denominational transmission units.

It will be noted that no slots 32 are provided on screens 16 to represent zero values, and consequently no zero slots 39 are provided on the scanning screen 37, but the numeral wheels 75 are provided with zeros in the starting or zero positions. In the event that zero is to be registered, the corresponding numeral wheel will turn through a complete revolution so that when the drive is discontinued, the numeral wheel in question will again be in its starting position in which zero is registered.

A complete transmission cycle will now be described. On setting a result screen 16 by means of keys 1 and 2 in accordance with price per unit and weight in question, handle 55 is pushed to the right. Movement of the handle 55 through its full range in one direction is sufficient to rotate the pinion 53 through about one turn and a quarter. This causes the main driving segment 52 to rotate around its pivot 57 and to turn pinion 53 which drives the shaft 48, and through key 63, and clutch 61, 60, the driving pinion 47. This causes pinions 46 and 106 to rotate. Pinion 46 turns shaft 41, the gear segments 80 and the scanning screen 37. Gear segments 80 are off-set in such a manner that they turn consecutively the toothed sleeves 82, clutches 94, and the printing numeral wheels 75, the arrangement being such that each scanning slot becomes coincident with the beam of radiant energy simultaneously with the positioning in printing position of the numeral individual to the particular slot, a certain period being allowed for the necessary time lag. As soon as one scanning slot 39 on scanning screen 37 coincides with a result slot 32 on result screen 16, the relay armature 96 of the particular transmission unit, which has been brought by its cam 98 into the working position, is attracted into position (Figures 7 and 8) by relay 38 which is actuated by the beam of light passing through slots 32 and 39 from the source 33 to the cell 35. Thus, the relay armature 96 causes its clutch fork 95 to swing around its pivot 100, thereby disengaging clutch 94 from wheel 108 and thus from numeral wheel 75, which is immediately stopped by pawl 109 coating with stop wheel 108. It is understood that only one relay armature 96 at the time is in the working position, all other armatures being in initial position (Figures 9 and 11). When the revolution of scanning screen

37 is completed, all numerals of the items represented by slots 32 on result screen 16 are transferred in this manner on to the numeral wheels 75. The clutch 61, being fixed to the shaft 54 (driven by the pinion 53) by the key 63, also rotates for about one turn and a quarter. The clutch 61 is, at the beginning of its forward turn, in the position shown in Figs. 20 and 22, its recess being engaged by the cam-shaped projection 60 on the gear 47, so that this gear 47 is also turned, but for one turn only, whereupon it is stopped by its pin 64 engaging the stop trigger 65, as shown in Fig. 23. The clutch 61, however, continues to be driven in the same direction for approximately a quarter-turn, whereby as viewed in Figures 22 and 20, it is forced to the right, the side slope of its recess riding up the slope of the cam-shaped projection 60 on gear 47, against the pressure of the spring 62 until the face of the clutch 61 rides on the top of the projection 60. This axial movement of the clutch 61 to the right causes its driving pin 70 to enter the hole 71 in the gear 72, which gear is now driven until the actuator handle 55 reaches the end of the slot 16 (Fig. 21), i. e. for approximately a quarter turn. As this gear 72 is in mesh with gear 73, fast on shaft 74, this shaft is also turned for approximately a quarter turn, i. e. an amount sufficient for the eccentrics 113 (Fig. 16) to cause the printing pad 120 to press the paper strip 121 on to the numeral wheels 75 (which are now not in motion) to take an imprint (Fig. 7). The handle 55 being now released, it is returned by the spring 71, whereby the various parts move in the reverse direction, the shaft 74 and the gears 73, 72 being returned first, since the pin 70 of the clutch 60 is still in engagement with the hole 71 in the gear 72. Thus, the printing pad 120 moves away from the numeral wheels 75 and at the same time gear 137 on shaft 74 turns pinion 134 or the delivery shaft 128, which causes the paper sheet 121 to move upwards through opening 159 in machine cover 145, whereupon it can be torn off on cutting blade 160. After the clutch 61 (and gears 72, 73) have been moved back approximately a quarter turn, the recess in the clutch 61 again coincides with the cam-like projection 60, whereupon the spring 62 forces the clutch 61 to the left, i. e. into the position shown in Fig. 22, thereby withdrawing the pin 70 from the hole 71 in the gear 72, so that the latter, together with gear 73 and the shaft 74, stops in the initial position. The clutch 61, now in engagement with the projection 60 of the gear 47, continues its return movement to the starting position, thereby restoring gears 46, 106, as well as gear segments 80 and cams 98 (Fig. 7) driven thereby, until the pin 64 again reaches the stop trigger 65 (Fig. 22) and the handle 55 is stopped on reaching the left-hand end of the slot 16 (Fig. 21). As the driving pins 107 on clutches 94 coincide respectively during the return movement with the holes in the wheels 108 each clutch slips into engagement under influence of spring 102 and turns the particular numeral wheel 75 back into initial position. It is understood that the illumination of the result screen is switched off as soon as the forward stroke of the transmission mechanism is completed.

This may be accomplished by providing a switch of known construction and illustrated in Figures 22, 23. A plunger 190 of non-conducting material is slidably mounted in a side wall of the bracket 67 and is pressed by a contact

spring 191 on to the tail of the trigger 65 above described. The contact spring 191 is secured to an insulator block 192 fixed to the side frame 44 of the machine structure, a contact blade 193 being also secured to the block 192. The spring 191 and the blade 193 are connected to conductors 194, 195 respectively, the other ends of which are connected to the main switch 163, Figure 2, and to the lamp 33, respectively. Thus, the circuit of the lamp 33 is closed by closing the spring 191 and the blade 193, and it is interrupted by withdrawing the spring 191 from the blade 193.

At the beginning of the forward stroke of the actuator 55 the trigger 65 is in the position of Figure 22; thereby it forces the plunger 190 to press the contact spring 191 on to the contact blade 193, thus closing the circuit of the lamp 33. The trigger 65 is kept in this position by its spring 69 until the gear 47 completes a full turn and the pin 64 swings the trigger 65 into the position shown in Figure 23, as previously described. Thereby the plunger 190 releases the contact spring 191, which is now free to move away from the contact blade 193, as shown in Figure 23. The trigger 65 remains in this position until the end of the return stroke of the actuator 55, when the pin 64 restores it to the position of Figure 22. Thus, the conductors 194, 195 remain disconnected, and the lamp 33 is switched off during the resetting movement of the transmission mechanism.

The necessary electrical devices comprise an amplifier 161 of any known construction adapted to produce quick and sufficient amplification, a transformer 162 and switch 163 for the circuit of the light sensitive cell and lamp. A rectifier and resistances may be arranged in any one of the known ways. If desired, a supplementary relay may be operated by the light sensitive cell for the purpose of controlling a stronger circuit (164, 165) for the relay 38 and the light sensitive cell 35 and lamp 33 may be replaced by any other suitable means of a like kind.

An embodiment in which a flat disc 166 is used as a scanning body instead of a cylinder 37, is shown in Figure 24. The scanning slots 167 are arranged along a spiral line.

In order to overcome any inaccuracy as to the respective positions of the slots in the screens 16 and 166, a series of narrow channels 168 may be arranged in front of the scanning screen 37 or 166 (as shown in Figure 24) in such a manner as to absorb any sideways illumination of the scanning slots 39 or 167.

The size of the light sensitive cell may be considerably reduced by arranging a condenser lens or a condensing reflector between the scanning screen and the cell.

A modified form of screen mechanism is illustrated in Figures 25A, 25B according to which only one key-board and one weight screen 169 is required, whereas there is provided a price screen 170 for each price per unit. The screen 169 is furnished with weight slots only, whereas each screen 170 is furnished with an area for slots representing the price per unit individual to this screen, and a second area for slots representing the multiplication results. All the price screens 170 and the single weight screen 169 are pivotally mounted on a common shaft 171.

The supporting arms 177 of the price screens 170 are each furnished near the shaft 171 with either a projection 176 substantially at right angles to the arm 177, or with a projection 181

which is a direct continuation of the arm 171 beyond the pivot point. The arrangement is such that the foremost (as shown in Fig. 25) screen 170 has a straight projection 181, the second (immediately behind) has a bent projection 176, the third screen 170 has again a straight projection 181, the fourth screen has again a bent projection 176, and so on, in alternate order. Each of the bent projections 176 is connected by a link 175 to the upper end of a lever 173, the lower end of which is pivotally connected to one of the price keys 172 of the three upper rows. Similarly, each of the straight projections 181 is connected by a link 180 to a lever 178 pivotally connected to one of the price keys 172 of the three lower rows. The levers 173, 178 are pivotally mounted on bars 174, 179, respectively, which are secured in the frame of the machine, and distancing bushes may be provided to keep the levers in proper axial distance from each other. The projections 176, 181 on the arms 177 are made alternately of different shape in order to facilitate a compact mounting of the screens 170 close to each other on the shaft 171, whereby the arms 177 of the screens may be provided with bosses (as shown) of appropriate thickness. The keys 172 are each marked with respective price per unit weight. The price screens 170 are each provided with ratchet teeth 183 arranged to coact with a stop pawl 184 extending transversely of the screens pivotally mounted on bar 185 and pressed towards the edges of the screens 170 by one or more springs 186. The weight screen 169 is provided with an arcuate plate 187 bearing a scale of weight graduations, said scale operating in conjunction with an indicating finger or an aperture in the cover plate. Furthermore, the weight screen is provided adjacent its lower end with a bar 188 fixed at right angles to the screen, said bar being arranged to coact with projections 189 on the price screens 170. On depressing one of the keys 172, the corresponding price screen 170 swings upwards and by reason of the projection 189 thereon engaging with the bar 188, the weight screen 169 is caused to move therewith, thereby causing the scale 187 on the plate to move relatively to the indicator finger or aperture until the desired weight comes into coincidence with the finger or appears through the opening in the cover plate; the finger pressure is then removed from the key 172 and the price screen 170 as well as the weight screen 169 are locked in this position by the stop pawl 184. The upper part of the edge of each of the screens 170 is provided with a plain portion 190 which extends slightly beyond the outer edge of the teeth 183 so that when a second price screen 170 is raised by the operation of one of the keys 172, the part 190 thereon pushes the pawl 184 to the right out of engagement with the teeth 183 of the first screen 170, thereby releasing same and permitting it to return into the initial position under the influence of its own weight. The advantage of this arrangement is that only one key-board is used and that the number of slots on screens 170 is considerably reduced.

When the invention is to be applied to, for example, a machine for printing railway tickets or the like and for registering and/or recording the fares in a total accumulator contrary to known machines for this purpose, only one printing device is used for printing tickets of every description whereby the fare is automatically 70

calculated and registered in accordance with distance and class or the like of travelling.

The machine employed for the purpose above referred to is substantially the same as that previously described, the main difference residing, as will be appreciated, in the form of the result screens 16; for example, the distances from one railway station to all other stations on the same route may be classified in a number of tariff zones, for instance, in 25 zones. There are also different kinds of tickets, say first, second and third class, week-end, return, child, excursion, etc., which may be classified in, for instance, 16 groups. According to this invention a screen 16 is provided for each of the 16 groups of tickets, each of said screens 16 containing the characteristics of all tickets belonging to a particular group. There is, for example, one screen 16 for third class week-end return tickets; this screen may be divided into as many horizontal rows as there are tariff-zones, say 25, each of said rows containing the symbols for (a) the tariff-zone, (b) for the group, which is, as will be understood, the same for all rows, and (c) for the fare to be paid.

The machine is, as before, provided with two key-boards 1 and 2. The keys 1 of the one bank are connected to the stops 10 coacting with the screens 16, said keys 1 being marked with the numbers of the tariff-zones and, if desired, also in a suitably abbreviated form with the stations belonging to the particular tariff-zone. However, in most cases, especially if there are too many stations in one tariff-zone, a code-number 35 is preferably used to indicate the stations for which the ticket is issued. The keys 2 of the other bank are connected to the screens 16 and are marked to indicate the kinds of ticket belonging to the screens 16 connected thereto.

Alternatively, an arrangement as shown in Figure 25 with only one key-board can be used, the stations being set by means of a scale 187. On the other hand, an indicator can be used instead of scale 187, said indicator being arranged to move along a scale fixed to the cover of the machine with the names of stations marked on it in a suitable manner.

A datum stamp may, if desired, be placed adjacent the printing device so that the tickets may be dated when being printed, and a duplicate of the ticket being printed may be made on a continuous strip for recording purposes.

The numeral wheels 75 may be arranged to print the code-number of the ticket group and of the station of destination; if desired, suitable abbreviations can be used. The paper reel 122 may be prepared by printing on it the name of issuing station and other standard wordings in suitable positions.

I claim:

1. In apparatus for registering information represented by similarly shaped but differently positioned light transmitting areas on a carrier, the transparency of said light transmitting areas being different to that of the carrier, scanning means having a plurality of groups of scanning light transmitting areas, all groups and all light transmitting areas within each group being adapted to pass successively through the scanning plane during one scanning operation, one group of scanning light transmitting areas being provided for each denomination of the information to be registered and one light transmitting area within each group being provided for each

possible value of the associated denomination, a source of light, a light sensitive device adapted to receive light transmitted from the light source through the carrier and scanning means, an electro-magnet controlled by said light-sensitive device, a plurality of transmission units, one for each denomination of the information to be registered, a clutch included in each transmission unit, all said clutches being controlled by said electro-magnet, means driven in synchronism with the scanning means for rendering each clutch operable only when its associated group of scanning light transmitting areas is in the scanning plane, a plurality of registering elements each of which is adapted to be driven by one of said clutches; and means for driving said clutches in succession and in synchronism with said scanning means.

2. Apparatus as claimed in claim 1 comprising a plurality of armatures each of which is adapted to operate one of said clutches, all said armatures being operable by the said electro-magnet, and a plurality of cams constituting the said means

driven in synchronism with the scanning means, said cams rendering said armatures successively operable by said electro-magnet.

3. Apparatus as claimed in claim 1 comprising a plurality of gear elements mounted in off-set relationship on a common shaft for driving said clutches in succession, each of said gear elements driving one of said clutches.

4. Apparatus as claimed in claim 1 wherein the driving connection between each clutch and the registering element driven thereby, comprises a gear wheel adapted to drive the registering element, a pin carried on each clutch adapted, when the clutch is moved, to be operatively engaged with, or disengaged from, the said gear wheel, and spring means tending to press each clutch and pin into operative engagement with the associated gear wheel, whereby during the return or resetting movement of the mechanism the pins drive the respective gear wheels to return the registering elements to the starting position.

DANIEL BRODO.
